UNITED STATES PATENT OFFICE.

DANIEL L. ADAMS, OF READING, PENNSYLVANIA.

SECTIONAL STEAM-BOILER.

SPECIFICATION forming part of Letters Patent No. 349,918, dated September 28, 1886.

Application filed June 17, 1886. Serial No. 205,418. (No model.)

To all whom it may concern:

Be it known that I, DANIEL L. ADAMS, a citizen of the United States, residing at Reading, in the county of Berks and State of Pennsylvania, have invented certain new and useful Improvements in Sectional Steam-Boilers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates especially to that class of steam-boilers known as "sectional" boilers, in which a series of chambered metallic sections are united by tubular joints and suitable bolts, the whole forming a boiler which ¹⁵ poses a large surface to the fire, with a comparatively small quantity of water which is kept in constant circulation, preventing the deposit of scale upon the parts exposed to the action of the fire, and thus giving the full ²⁰ effect of the heat which may be conducted through the metal of the sections to the water for its conversion into steam, as such scale is a non-conductor of heat, and, when the chambers of a boiler are thickly lined therewith, ²⁵ it prevents the heated metal from coming in contact with the water, thus causing great waste of fuel and limited production of steam.

The object of this invention is to improve the construction of this class of steam-boilers ³⁵ by so forming the sections that when properly arranged and connected they make a fire-box capable of receiving its supply of fuel from the ordinary end door, or through the top, so as to form a magazine or self-feeding furnace, ⁴⁰ the several sections forming the grate upon which the fuel rests during combustion, devices for clearing the spaces between said grates, and also a combustion-chamber in the rear of the fire-box so arranged as to insure a ⁴⁵ complete burning of the gases rising from the fuel.

A further object is to arrange the setting or casing within which the boiler is inclosed in such a manner that the radiated heat from the ⁵⁰ outer surface of the boiler may be utilized in warming air for heating rooms or other pur-

poses; and the invention consists in the construction and combination of the several parts in such a manner as to accomplish the above-named objects, as hereinafter fully described, ⁵⁵ and specifically stated in the claims.

In the accompanying drawings, Figure 1 is a side elevation of the boiler and its connections, a part of the outer casing being broken away to show clearly the relative arrangement ⁶⁰ of the boiler-sections. Fig. 2 is a vertical longitudinal section through the boiler, its supporting-base, and the case by which its upper part is surrounded. Fig. 3 is a transverse vertical section on the line *y y*, Fig. 1, illustrating the ⁶⁵ relative arrangements of the boiler sections with the other parts at that point. Fig. 4 is an elevation of the front section of the boiler, containing the feed-door. Fig. 5 shows a part of one of the boiler-sections above the ash pit, ⁷⁰ with the grate-cleaning device in position. Fig. 6 represents a vertical section of one of the boiler-sections in that part forming the combustion-chamber. Fig. 7 is a perspective view of one section of the boiler in the part ⁷⁵ forming the fire-box. Fig. 8 presents a plan of two sections forming a part of the grate. It also shows the manner in which the joints between the several sections are made. Fig. 9 is a perspective view of one of the gaskets ⁸⁰ used in making the joints between the sections.

Like letters of reference denote corresponding parts in all the figures.

This boiler is formed of a series of hollow cast-iron sections of certain specific forms, by ⁸⁵ the combination of which in different ways the form of the boiler, as a whole, may be changed to suit the requirements of the situation in which it is placed and the work it is desired to do, the principal use being to heat ⁹⁰ buildings, for which purpose it is admirably adapted, as the principle of construction enables it to be readily adapted to the size of the building it is to heat, while the base which forms the ash-pit and upon which it rests, together with the outer case covering the steam-producing part render it complete and in form to be readily placed wherever wanted without the use of brick-work or other setting. This base *A* is of cast-iron, and is divided into three ⁹⁵ compartments, the principal one being the ash-pit *A'*, the bottom of which inclines toward the ¹⁰⁰

door B, which is hinged at the top to lugs *a*, attached to the front of the base, and rests, when closed, upon inclined flanges projecting from the front of the base. This door B is also provided with an air or draft opening, *a'*, closed by an adjustable cover, so that the amount of air entering the ash-pit may be readily gaged to suit the wants of the fire. In the rear of this ash pit and partly supported by the brackets B' is a chamber which is divided by the sliding diaphragm or damper B'' into two compartments, A'' A³, the upper one forming a combustion-chamber where the gases from the fuel mingle and are completely burned. The lower chamber forms a smoke-box and is connected by a suitable opening, as *a''*, with the smoke-flue C. At the outer end of this smoke-flue is placed a cleaning-door, C', through which the ashes or soot accumulating in the smoke-box A³ may be readily removed when necessary.

It will be seen that the adjustable air-opening in the ash-pit door, together with the sliding damper B'', affords means for completely controlling the admission of air to the fuel and escape of the gaseous products of combustion therefrom, and by connecting both or either of them to one of the well-known regulators operated by the steam-pressure the intensity 30 of the fire and amount of steam generated will be automatically regulated.

It will be observed that the upper covering of the base A, formed of the grate bars, is inclined from the front of the furnace to its rear, 35 the grate-bars and the sections of which they are a part being so located upon the side walls of the base as to make this covering inclined. Upon this base, therefore, are carried the boiler-sections 1 2 3 4 5. These sections are all formed 40 of cast-iron, as shown in the detail Figs. 4, 5, 6, 7, and 8 of the drawings. They are cast hollow, so that the water has a free circulation through every part, and are provided with four or more rectangular openings, *b b*, through 45 which the water-circulation is kept up, and through which the bolts *b'* that connect the sections pass, a rectangular gasket, *b''*, having an opening through it corresponding with the openings *b* in the sections, being placed between 50 the adjoining faces of each two sections surrounding the openings *b*. These gaskets form the joint packing, and when the nuts upon the bolts *b'* (which pass through the several sections) are screwed up they are all firmly connected, so as to form a complete boiler with a 55 free water-circulation throughout.

As the packing used to make the joints and the slight projection of the parts upon which it rests would leave an opening between the several sections of the boiler through which the smoke and other products of combustion would pass, it becomes necessary to provide means for closing this opening, which I accomplish by providing the several sections with projecting 60 tongues *c* upon one side, which enter groove *c'* in the side of the adjacent section. Thus it will

be seen that the sections have a tongue on one side and a groove upon the other so arranged that when the several sections are brought together in a boiler all the openings, except 7c those required for the introduction of fuel and exit of the products of combustion, are closed.

In the arrangement of the several sections to form a boiler I will describe that shown in the drawings, but it will be understood that 75 this arrangement may be changed to suit the different situations in which the boiler is placed or purpose to which it is applied. Section 1, which is placed at the front, is provided with the projecting flanges *e*, against 80 which the door D, hinged to lugs *e'*, rests when closed. This door is provided with an inner plate, D', held at a short distance from the outer plate by suitable stud-bolts, an air-opening, *e''*, being formed in the outer plate. The air 85 passing through this opening strikes against the inner plate, is deflected by it and passes out around its edges, as shown by the arrows in Fig. 2, thus performing the double purpose of 9c keeping the door comparatively cool and admitting air above the grate to assist in the combustion of the fuel. The next section is numbered 2 in the drawings, and is shown detached in Fig. 7. It consists, simply, of a rectangular hollow casting having the large 95 open space E in its center. The lower bar, G, of this serves as one of the grates, and is provided on one side with short projections *f*, which partly fill the space between it and the lower bar, G, of the next section, 100 numbered 3. This section has the same construction of lower bar to serve as a grate as the preceding, but the open space E is of less height, leaving a larger water-space above it. This section is also provided with lugs *g*, to 105 which the hopper H of the magazine is secured by bolts *g'*. This hopper extends rearwardly for four sections, and is then secured by similar bolts to the lugs of a boiler-section identical in construction with section 3 just described. This hopper is provided with a cover, H', and is used in the usual manner. The coal or other fuel being placed therein and falling upon the grate burns about its edges, and as 110 it consumes the supply is automatically kept 115 up by the settling of the fuel in the hopper.

The following four sections (marked 4 4 4 4 in the drawings) are identical in construction, but differ from those heretofore described, in the fact that they have no cross-bar at top, 120 this space being left open for the descent of the fuel placed in the hopper. The succeeding section (also marked 3) is identical with the one in front of the hopper. The next section is the same as that heretofore described 125 and marked 2; but this is followed by a section (marked 5) which differs from those heretofore described in having a much smaller opening, E, the lower cross-bar, G', being carried much higher than those preceding, which 130 act as grate-bars. The reason for this is that the part G' acts as a bridge-wall, partially sep-

arating the fire-box from the combustion-chamber I, which follows it. This combustion-chamber is formed by placing four sections of the same construction as that heretofore described as No. 2, side by side, and following with a section, 5, which forms the rear end of the boiler, the opening in said terminal section being closed by a plate, k, thus completing the construction of the boiler so far as its water-carrying portions are concerned.

In order to clean the grate two shafts, L L, are placed lengthwise of the ash-pit beneath the grate, each of them being provided with arms h h. These arms carry rods h', upon which, at distances equal to the spaces between the grates, are placed the combs J J, the teeth of which project upward between the sections G, forming the grate-bars. The outer ends of the shafts L, which project in front of the ash-pit, are squared to receive a shaking-lever, by means of which an oscillating motion is given to the shafts. This motion, through the agency of the arms h, imparts a vertical as well as a lateral movement to the rods h' and combs, the teeth of which consequently pass upward through the interstices between the bars, and at the same time move from side to side, effectually breaking up clinkers and disengaging the ashes which fall into the ash-pit.

It will be observed that the several sections of the boiler form a continually-ascending series, which facilitates the circulation of the water and escape of steam to the highest point where a connection with the steam-pipe is made, as at m, the water being introduced at the opposite end of the boiler, as at n. Suitable openings are also formed in the two end sections, as at o, for the purpose of washing out the boiler when desired.

As the outer surface of the boiler presents a large heat-radiating surface, it becomes desirable to provide means by which this can be accomplished. I have therefore provided a tin-lined case, P, which rests at its lower edge upon the base A, but completely incloses the several sections of the boiler, a suitable space being left between the outer surface of said sections and the inner surface of the case for the passage of the air, which enters by the cold-air pipe P', and after having been heated by contact with the outer surface of the boiler, passes out through the pipe P" to the room or rooms where its heat is to be utilized.

It will be apparent, as heretofore stated, that many changes may be made in the number and arrangement of the sections composing the boiler to suit the circumstances in which the same is to be placed. For instance, should the cellar or other room in which the boiler is situated have a low ceiling, rendering it inexpedient to use the magazine, the part of the boiler occupied by sections 4 4 will be filled with sections 2 2 and the fuel supplied wholly through the door D. Again, the combustion-chamber in rear of the fire-box, as well as the fire-box itself, may be readily enlarged or diminished by adding to or taking from the number of sections employed in each.

A further great advantage gained by constructing boilers in this manner is the great facility offered by its peculiar construction in making repairs, as should a section be injured, it may be easily removed and a new one substituted.

Having thus described my invention, what I claim as new, and desire to secure by Letters Patent, is—

1. The herein-described steam-boiler having sections arranged to form an inclined base; which is provided with the ash-pit, combustion-chamber, and smoke-box, said combustion-chamber and smoke-box being separated by a sliding damper, as set forth.

2. The base constructed as shown and described, in combination with the boiler-sections, the lower parts of which form the furnace grate-bars and shaking devices carried upon oscillating rock-shafts, with both an upward and a lateral movement between said grate-bars, as specified.

3. In a sectional steam-boiler, the combination of the several sections arranged upon an incline, with the base constructed as shown, and the outer case surrounding the sections and provided with air-ducts, as and for the purpose stated.

4. The steam-boiler composed of sections arranged as described, in combination with the magazine and fuel-hopper attached to said sections in the manner specified.

In testimony whereof I affix my signature in presence of two witnesses.

DANIEL L. ADAMS.
